LA MOTTE SMITH, OF SYRACUSE, NEW YORK.

SUPPORT AND SHOCK-ABSORBER FOR TYPEWRITERS.

Application filed October 25, 1921. Serial No. 510,217.

To all whom it may concern:

Be it known that I, LA MOTTE SMITH, a citizen of the United States, and a resident of Syracuse, in the county of Onondaga and State of New York, have invented a certain new and useful Support and Shock-Absorber for Typewriters, of which the following is a specification.

This invention has for its object a support and shock absorber device for typewriter machines, which is particularly simple and economical in construction, and highly efficient and durable in use, and on which the typewriter frame can be readily mounted and secured.

The invention consists in the novel features, and in the combinations and constructions hereinafter set forth and claimed.

In describing this invention, reference is had to the accompanying drawings in which like characters designate corresponding parts in all the views.

Figure 1 is a side elevation of one of the supports, the contiguous parts of the typewriter frame being also shown.

Figure 2 is a sectional view looking downwardly, taken on line 2—2, Fig. 1.

These devices are adapted for typewriting machines manufactured by the well known L. C. Smith & Bros. Typewriter Co., or for similar machines, having vertical screws in the lower edges of each of the side members of the frame for attaching the machine to a desk.

In the drawing, 1 designates the side members of the frame, of a typewriting member, each of which has front and rear rests or feet 2, 3 and a screw 4 threading vertically into the lower edge of each side member near the front foot 2. The screws 4 are practically shoulders depending from the lower edge of the typewriter frame.

My typewriter support and shock absorber comprises a pair of resilient strips 5 having feet 6 at their front and rear ends whereby the strip 5 is offset from the desk or table, front and rear brackets 7, 8 mounted on each strip and having portions 9 overhanging the strip and formed with a slot 10 opening through the edge of the overhanging portion for receiving one of the feet of the typewriter.

Preferably, the overhanging portions 9 extend in the direction of the strip and the slots 10 open through the front end edges of the overhanging portions so that the type-

writer frame can be first placed on the strips with the feet thereof in alinement with the slots and then the frame moved rearwardly moving the feet into the slots. These brackets with their slots are practically crotch plates.

Means is provided for locking the frame from movement after it has been placed in juxtaposition on the strips and as here shown, one of the brackets 7, 8 as the front bracket 7 of each strip is formed with a slot 11 opening into the slot 10 through the bottom or inner end thereof, the slot 11 being of less width than the slot 10 but being of sufficient width to receive the fastening screws 4, and a latch 13 is mounted on each front bracket and is movable to close the entrance of the slot 11 and thus hold the typewriter frame from movement owing to the fact that the screw 4 is held from movement out of the slot by the latch.

In the illustrated embodiment of my invention, the latch 13 is pivoted at 14 on a vertical pivot to the front bracket of each strip 5 and has an arc-shaped slot 15 for receiving the screw 4, and an arm 16 movable across the entrance of the latter slot, the latch 13 being preferably mounted on the upper side of the overhanging portion 9 of the front bracket 7 of each strip.

The rear bracket 8 of each strip is also shown as formed with a slot similar to the slot 11 but such slot is present in the rear bracket owing to the fact that both front and rear brackets are made with the same dies.

In operation the typewriter is placed so that it stands on the back member of the frame, the screws 4 are turned in the screw holes directly behind the front rubber feet of the frame are adjusted so that the rubber feet project beyond the heads of the screws.

The shock absorbing device is then placed in position with the feet of the typewriter in the slots 10 and the screws 4 in the slots 11. The screws 4 are then adjusted to fit in the slot 11 loosely. The latch is then moved on its pivot to close the slots 11.

The machine with shock absorber attached thereto is then set on the desk and the shock absorbers secured to the desk by screws passing through the feet of the shock absorber.

What I claim is:

1. A support and shock absorber device for typewriters having feet and depending

pins depending from the lower edges of the typewriter frame near one of the feet, said devices comprising a bracket formed with an overhanging horizontal portion, said portion being formed with openings for receiving one of the feet of the typewriter and the adjacent pin and means coacting with the pin for holding the frame from displacement from the bracket, substantially as and for the purpose described.

2. A support and shock absorber device for typewriters having feet and depending pins depending from the lower edges of the typewriter frame near one of the feet, said devices comprising a bracket formed with an overhanging horizontal portion, said portion being formed with openings for receiving one of the feet of the typewriter and the adjacent pin, and a latch pivoted to the overhanging portion of the vertical feet, and movable horizontally into engagement with said pin, substantially as and for the purpose specified.

3. A typewriter support comprising front and rear crotch plates for receiving the feet of the typewriter frame, one of said crotch plates having a slot opening into the inner end of the crotch for receiving a depending pin on the frame adjacent one of the feet on the frame, and a latch carried by such crotch plate and movable across the entrance of the slot to lock the plate in the slot, substantially as and for the purpose set forth.

4. A support and shock absorber device for typewriters having feet, and pins depending from the lower edges of the typewriter frame, said device comprising a resilient strip having supporting feet at its ends, a bracket mounted on the intermediate part of the strip and formed with a portion overhanging the strip and extending in the direction of the strip, the overhanging portion being formed with a lengthwise slot opening through the end edge thereof for receiving one of the feet of the typewriter frame, and with a slot of less width than the former slot and opening through the inner end wall of the former slot for receiving a depending pin on the lower edge of the typewriter frame, and means for closing the entrance of the latter slot, substantially as and for the purpose specified.

5. A support and shock absorber device for typewriters having feet, and a pin depending from the lower edges of the typewriter frame, said device comprising a resilient strip having supporting feet at its ends, a bracket mounted on the intermediate part of the strip and formed with a portion overhanging the strip and extending in the direction of the strip, the overhanging portion being formed with a lengthwise slot opening through the end edge thereof for receiving one of the feet of the typewriter frame, and with a slot of less width than the

former slot and opening through the inner end wall of the former slot for receiving the depending pin on the lower edge of the typewriter frame, and means for closing the entrance of the latter slot, said means comprising a latch carried by the bracket and movable across the entrance of the latter slot where it opens into the former slot, substantially as and for the purpose set forth.

6. A typewriter support and shock absorber comprising a pair of base strips having supporting feet at their ends, front and rear crotch plates carried by each strip for receiving the feet of the typewriter frame, one of said crotch plates having a slot opening into the inner end of the crotch for receiving a depending headed pin on the frame, and a latch carried by such crotch plate and movable across the entrance of the slot to lock the headed pin in the slot, substantially as and for the purpose specified.

7. A support and shock absorber device for typewriters having feet and pins depending from the lower edges of the typewriter frame near one of the feet, said devices comprising a resilient strip having supporting feet at its ends, a bracket mounted on the strip and formed with a portion overhanging the strip, said portion being formed with openings for receiving one of the feet of the typewriter and the adjacent pin, substantially as and for the purpose described.

8. A support and shock absorber device for typewriters having feet and pins depending from the lower edges of the typewriter frame near one of the feet, said devices comprising a resilient strip having supporting feet at its ends, a bracket mounted on the strip and formed with a portion overhanging the strip, said portion being formed with openings for receiving one of the feet of the typewriter and the adjacent pin, and means coacting with the pins for holding the frame from detachment from the strip, substantially as and for the purpose specified.

9. A support and shock absorber device for typewriters having feet and pins threading into the lower edges of the typewriter frame, said device comprising a resilient strip having supporting feet at its ends, a bracket mounted on the strip and formed with a portion overhanging the strip, said portion being formed with an opening for one of the feet of the typewriter and with a slot leading from said opening for receiving the adjacent pin of the typewriter frame, and a latch carried by the bracket and movable across the entrance of said slot, substantially as and for the purpose set forth.

In testimony whereof, I have hereunto signed my name, at Syracuse, in the county of Onondaga, and State of New York, this 13th day of October, 1921.

LA MOTTE SMITH.
